(57) **CLAIM**

The ornamental design for a charger for electric vehicle as shown and described.

DESCRIPTION

1. Charger for electric vehicle
- 1.1 : Front perspective view
- 1.2 : Back perspective view
- 1.3 : Front
- 1.4 : Back
- 1.5 : Left
- 1.6 : Right
- 1.7 : Top
- 1.8 : Bottom
- 1.9 : Front perspective view, shown in a configuration of use
The broken lines illustrate portions of the article that form no part of the claimed design.

1 Claim, 9 Drawing Sheets(56)
